UNITED STATES PATENT OFFICE.

HARLEY H. LA VERCOMBE, OF DETROIT, MICHIGAN.

DEVICE FOR EXPANDING REAMERS.

1,353,535.

Specification of Letters Patent. Patented Sept. 21, 1920.

Application filed February 24, 1919. Serial No. 278,857.

To all whom it may concern:

Be it known that I, HARLEY H. LA VERCOMBE, a citizen of the United States of America, residing at Detroit, in the county of Wayne and State of Michigan, have invented certain new and useful Improvements in Devices for Expanding Reamers, of which the following is a specification, reference being had therein to the accompanying drawings.

In Patent No. 1,268,365, issued to me on June 4, 1918, there is a method illustrated of reforming reamers by locally compressing the flutes or teeth separately of a reamer that has been heated between the cutting edge and the root of each tooth, whereby the cutting edges are projected out to the desired diameter of the finished tool. The invention herein relates to one preferred form of device for carrying out this method accurately and rapidly, the invention possessing not only special adaptability for the purpose but also ease of adjustment for different types or sizes of reamers.

The invention consists in the matters hereinafter set forth, and more particularly pointed out in the appended claims.

In the drawings,

Figure 1 is a plan view of a device embodying features of the invention; and

Fig. 2 is a view in side elevation of the device together with a coöperating punch.

As herein indicated a die bed 1 is formed of suitable design to combine strength and rigidity with lightness, and is arranged to clamp on the bed of a press. An anvil block 2 is longitudinally movable on the bed, so that a post 3, thereon, on which rests a pivotally secured arm 4, may be accurately brought into adjustment with a suitable punch 5 carried in the head of the press on which the bed is clamped. For ease of positioning the end of the block, an adjusting screw 6 is in screw-threaded engagement with a lug 7 of the block and in rotatable engagement with the anvil block 2; a clamping stud 8 holds the block in adjusted position.

A reamer carrier is mounted on the bed 1 opposite to the anvil block 2. In preferred form this is a yoke 9 that may be adjusted back and forth in relation to the anvil block by a hand screw 10 and may be clamped in position by any suitable bolt 11. A tool support is longitudinally adjustable on the yoke in widely separated bearings 12,

the support preferably taking the form of a bar 13 that is slidable in the bearings 12 and is held in position by a set screw 14, so as to bring a pair of parallel arms 15 that are keyed or otherwise non-rotatably secured to the bar 13 and held against longitudinal displacement by set screws 23, in desired relation, together with center rests 16 and 17 thereon, to the punch 5 and the anvil member 4.

Preferably the center 17 is cut away as indicated to allow free movement of the punch 5, across the same, and is longitudinally adjustable in the companion arm 15 where it is held in fixed position by a set screw 18. The center 16 is longitudinally movable in the companion arm 15, being normally projected by a spring 19 that encircles a stem 20 of the center and is in a counterbored opening of the arm 15 in which the center 16 is movable.

As a result of this construction a reamer, such as indicated at 21 is quickly mounted on the centers 16 and 17 and by proper adjustment of the parts of the device, each rib or flute 22 may be brought successively to rest on the anvil member 4 while the punch 5 operates thereon in the way called for in the method application before referred to. Because of the adjustability of the parts on the die bed, and of the tool carrier proper in the yoke, the tool may be readily adjusted for reamers of any size and length while the flutes of the reamer may be rapidly brought into position for operation by rotation of the reamer forward, the pivoted anvil arm permitting the rotation of the reamer counterclockwise as indicated by the arrows.

Obviously, changes in the details of construction may be made without departing from the spirit of my invention and I do not care to limit myself to any particular form or arrangement of parts.

What I claim is:—

1. A reamer reforming device comprising a bed adapted to be secured on a press bed and provided with an adjustably secured anvil and with means for supporting a reamer in operative relation to the anvil so that the reamer flutes may be brought successively into operative position on the anvil, said means being adjustable to hold any sized reamer, and a punch arranged to co-operate with the anvil in treating the flutes of a positioned reamer.

2. A reamer reforming device comprising a bed adapted to be secured on a press bed, an anvil member adjustably mounted on the bed, reamer holding means adjustably mounted on the bed and adapted to maintain an inserted reamer in operative relation to the anvil whereby the flutes of the reamer may be successively turned on the anvil, the structure being adjustable to hold any sized reamer, and a punch arranged to coöperate with the anvil on the flutes of the reamer.
3. A reamer reforming device comprising a bed adapted to be secured on a press bed, an anvil block movable adjustably on the bed, an anvil arm pivoted on the block, an anvil post adapted to support the outer end of the anvil arm when in operative position, a reamer supporting yoke adjustably mounted on the bed, reamer centers adjustably mounted on the yoke and adapted to rotatably support a reamer on its centers with a flute thereof resting on the anvil arm, and a punch arranged to coöperate with the anvil arm on the flutes of the reamer.
4. A reamer reforming device comprising a bed adapted to be secured on a press bed, an anvil block adjustable transversely on the bed, an anvil post on the block, an anvil arm pivoted on the anvil block to rest on the post, a yoke adjustable to and from the anvil block, a pair of yoke arms adjustable to and from each other in parallel relation on the yoke, a pair of centers mounted in alinement on the arms, one of the centers being yieldingly projected to-
ward the other, and a punch arranged to coöperate with the anvil arm in the treatment of a tooth or flute of a positioned reamer.
5. In a device for reforming reamers, and wherein the reamer flutes are subjected to reforming treatment by a punch individually, an anvil positionable to support an individual flute in the path of movement of the punch, an adjustable support for the anvil, and adjustable means for supporting a reamer to locate a flute thereof in treatment-receiving position relative to the anvil.
6. A device of the type of claim 5, characterized in that the positioned anvil is movable in the presence of a positioned reamer to permit a plurality of flutes of the reamer to be successively placed in position for treatment.
7. In a reamer reforming device adapted to be operatively positioned relative to a punch, a bed adapted to be secured on a press bed and provided with an adjustably-secured anvil and with means for supporting a reamer in operative relation to the anvil so that the reamer flutes may be brought successively into operative position on the anvil relative to the punch, said means being adjustable to support any sized reamer.

In testimony whereof I affix my signature in the presence of two witnesses.

HARLEY H. LA VERCOMBE.
